US0D1042619S

(12) **United States Design Patent** (10) Patent No.: **US D1,042,619 S**
(45) Date of Patent: ** Sep. 17, 2024

(54) **PRINTER**

(71) Applicant: **FUJIFILM Corporation**, Tokyo (JP)

(72) Inventors: **Hidetoshi Kimura**, Yokohama (JP);
Masahiko Yamamoto, Yokohama (JP)

(73) Assignee: **FUJIFILM CORPORATION**, Tokyo
(JP)

(**) Term: **15 Years**

(21) Appl. No.: **29/811,303**

(22) Filed: **Oct. 13, 2021**

(30) **Foreign Application Priority Data**

Apr. 16, 2021 (JP) ..... 2021-008123 D

(51) **LOC (14) Cl.** **14-02**

(52) **U.S. Cl.** **D18/53**

(58) **Field of Classification Search**

GROUP, PLLC

(57) **CLAIM**

The ornamental design for printer, as shown and described.

DESCRIPTION

FIG. 1 is a front view of a printer showing our new design;

FIG. 2 is a rear view of the printer;

FIG. 3 is a top plan view of the printer;

FIG. 4 is a bottom plan view of the printer;

FIG. 5 is a right side view of the printer;

FIG. 6 is a left side view of the printer; and,

FIG. 7 is an oblique view of the printer.

The broken lines immediately adjacent to the shaded areas depict the bounds of the claimed design while all other broken lines are directed to environment.

1 Claim, 7 Drawing Sheets
